(57) **CLAIM**

The ornamental design for a bottle, as shown and described.

DESCRIPTION

FIG. 1 is a front perspective view of embodiment one, of a bottle, showing our new design;

FIG. 2 is a left-side elevational view of embodiment one;

FIG. 3 is a right-side elevational view of embodiment one;

FIG. 4 is a front view of embodiment one;

FIG. 5 is a back view of embodiment one;

FIG. 6 is a top view of embodiment one;

FIG. 7 is a bottom view of embodiment one;

FIG. 8 is a front perspective view of embodiment two, of a bottle, showing our new design;

FIG. 9 is a left-side elevational view of embodiment two;

FIG. 10 is a right-side elevational view of embodiment two;

FIG. 11 is a front view of embodiment two;

FIG. 12 is a back view of embodiment two;

FIG. 13 is a top view of embodiment two;

FIG. 14 is a bottom view of embodiment two

FIG. 15 is a front perspective view of embodiment three, of a bottle showing our new design;

FIG. 16 is a left-side elevational view of embodiment three;

FIG. 17 is a right-side elevational view of embodiment three;

FIG. 18 is a front view of embodiment three;

FIG. 19 is a back view of embodiment three;

FIG. 20 is a top view of embodiment three; and,

FIG. 21 is a bottom view of embodiment three.

The broken lines in the figures illustrate the portions of the design that form no part of the claimed design.

1 Claim, 18 Drawing Sheets
